SLOTTED TUYÈRE FOR UNDERFEED STOKERS

Haskell C. Carter, Portland, Oreg., assignor to
Iron Fireman Manufacturing Company, Portland, Oreg.

Application February 19, 1938, Serial No. 191,476

6 Claims. (Cl. 110—45)

This invention relates generally to underfeed stokers, and particularly to a slotted tuyère to be used in conjunction therewith.

The main object of this invention is the construction of a tuyère which will permit expansion and contraction of the tuyère elements under changes in temperature without detracting from the utility of the tuyère itself.

The second object is to construct a tuyère element which is easy to install and less difficult to seal against air leakages than are tuyères which are built up of a number of small sections.

The third object is to improve the burning conditions by insuring a more uniform diffusion of the air over the fuel bed.

The fourth object is to add to the life of the tuyère element by holding it to an integral form at a place remote from the zone of high temperatures.

20 I accomplish these and other objects in the manner set forth in the following specification as illustrated in the accompanying drawing, in which:

Fig. 1 is a perspective view of a complete tuyère.

Fig. 2 is a section taken along the line 2—2 in Fig. 1.

Fig. 3 is a fragmentary section through a furnace showing the retort installed therein and the tuyère element mounted on the retort.

Similar numerals refer to similar parts throughout the several views.

Referring in detail to the drawing, there is shown a wall 18 upon which is mounted the boiler 11. Upon the floor 12 is mounted a retort 13, such as are commonly employed in underfeed stokers. Upon the retort 13 is mounted the tuyère section 14. A table 15 surrounds the tuyère section 14 and extends to the wall 18.

40 Referring particularly to the tuyère section 14, it will be noted that same has a cylindrical outer surface 16 and a sloping inner surface 17. The space 18 between the inner wall 19 and the outer wall 20 constitutes a means for supplying air to the ports 21. Air enters the space 18 through the openings 22 from the retort section 13.

It is desirable to provide the underside 23 of the tuyère with an extension 24 which projects into the retort 12 and facilitates the centering of the tuyère section 14 with relation to the retort 13.

It will be noted that around the upper edge of the tuyère 14 are formed a plurality of castles 25 having inner and outer ports 26. Vertical slots 27 extend downwardly between pairs of castles 25

to a point below the bottom 28 of the lowermost port 21. The slots 27 range from $\frac{1}{4}$ " to $\frac{1}{2}$ " in width. The side walls 29 connect the inner and outer walls 19 and 20 on each side of each slot 27. In some cases, especially with the larger tuyères, it is desirable to provide the V-notches 30 midway between the slots 27 for the purpose of further detracting from the distorting influence of temperature changes. 5

In the drawing are shown the lugs 31 which 10 are disposed around the lower side of the tuyère 14, that is, being merely employed for the purpose of holding the tuyère 14 in its proper relationship.

It is a well known fact that tuyères have long 15 constructed for underfeed stokers in which the tuyère element was unitary. Such tuyères, however, were found to be objectionable owing to the "growth" of the upper portion of the tuyère caused by the intense and prolonged heating 20 thereof until the tuyère element itself became fractured as a result thereof. This led to the adoption of a sectional tuyère, which, although having certain advantages as far as breaking was concerned, had other disadvantages such as 25 the cost of manufacture and installation, the difficulty of sealing against air leakages, holding same in position and other minor faults.

This brought about the adoption of a one piece tuyère provided with the slots 27 which prevent 30 the "growing" stresses from reaching the lowermost portion of the tuyère which, of course, is the portion of the tuyère that holds the uppermost portions together.

I claim:

1. A unitary circular tuyère element having air outlet openings in the walls thereof and having radial slots formed through the top thereof extending below the lowermost air outlet.

2. A unitary circular tuyère having a converging inner wall and a cylindrical outer wall spaced therefrom and having air outlet openings formed in the inner wall, said tuyère having radial slots formed therein extending from the top thereof to a plane below the lowermost air outlet. 40 45

3. A unitary circular tuyère element having a converging inner wall and a cylindrical outer wall and having air outlets along the uppermost portion of the inner wall and having radial expansion slots formed through both the inner and outer walls from the top thereof to a plane below the lowermost air outlet. 50

4. A circular tuyère element comprising inner and outer walls and having an air space between said walls, said inner walls having air outlet 55

- slots formed therein communicating with said air space, said tuyère having radial slots formed therethrough from the top thereof to a point below the lowermost air outlet but not communicating with said air space.
5. A tuyère element consisting of an integral circular ring having formed on the top side thereof a plurality of arcuate elements uniting to form a circular fire pot separated by radial channels extending from the top thereof to a point below that portion of the tuyère which is exposed to intense heat.
- 10

6. A tuyère of the class described having circular inner and outer walls and having an annular row of castles formed around the top thereof from which air may escape inwardly and outwardly, said castles being divided by radial slots which extend downwardly toward the bottom of the tuyère and subdivided by V-notches which extend approximately to the bottom of the castles.
